WALL DISPLAY FRAME FOR A TASSEL

Kenneth E. Kampfe, Omaha, Nebr., assignor to Paul A. Willsie Company, Omaha, Nebr., a corporation of Nebraska

Filed Sept. 24, 1962, Ser. No. 71,833

Term of patent 14 years

(Cl. D80—10)

FIG. 1 is a front elevational view of a wall display frame for a tassel embodying my new design; and

FIG. 2 is a sectional view of the same taken along the line 2—2 of FIG. 1 in the direction of the arrows.

The broken line showing of a tassel in FIG. 1 and the fragmentary broken line showing of a tassel in FIG. 2 are for illustrative purposes only.

I claim:

The ornamental design for a wall display frame for a tassel, as shown and described.
